UNITED STATES PATENT OFFICE.

STANDISH S. BUDLONG, OF ROCKFORD, ILLINOIS.

LAVATORY FIXTURE.

Application filed May 23, 1921. Serial No. 471,792.

To all whom it may concern:

Be it known that I, STANDISH S. BUDLONG, a citizen of the United States, residing at Rockford, in the county of Winnebago and

5 State of Illinois, have invented certain new and useful Improvements in Lavatory Fixtures, of which the following is a specification.

This invention pertains to lavatory fixtures of that class adapted for use in public and private lavatories for drying the hands and face by means of a current of heated air.

One of the primary objects of my invention is to provide a lavatory fixture of the character described constructed in a unique and novel manner with the view to simplicity and durability, and to enable the upward delivery of a wide-spread current of 10 heated air close to the heater.

Another important object is to provide a lavatory fixture in the form of a pedestal having a lower air inlet and an upper air delivery nozzle, a blower and a heater so arranged in the pedestal between said inlet and nozzle as to produce a most effective air current for drying purposes, and also to permit of quick removal of the heater and the blower from the pedestal.

25 Still another object is the provision of a lavatory fixture characterized by a hollow pedestal having an open top adapted to be covered by a perforate grate which constitutes the air nozzle, and heating and blower units adapted to be positioned in the pedestal through the open top thereof. A further object in this regard is the provision of electric connectors arranged in such novel manner that an electric circuit will be established 30 by placing said heater and blower units in operative position within the pedestal. As a result of this construction, the heater and blower units may be made interchangeable and may be quickly and easily removed and 35 replaced by others without regard to the electric connections. In other words, such connections will be automatically established by placing said units in operative position.

40 My invention also contemplates a lavatory fixture of the character described in which the blower and heater units are nested concentrically in the pedestal forming a continuous air channel in alignment with the delivery nozzle at the top of the pedestal.

45 I have also aimed to devise a lavatory fix-

ture of such novel design as to enable its production at a comparatively low cost, and to permit of repairs and replacements at a minimum cost.

Other objects and attendant advantages 60 will be appreciated by those familiar with this art as the invention becomes better understood by reference to the foregoing description when considered in connection with the accompanying drawings, in which— 65

Figure 1 is a vertical sectional view through a lavatory fixture embodying my invention;

Fig. 2, an enlarged horizontal sectional view taken substantially on the line 2—2 of 70 Fig. 1;

Fig. 3, a fragmentary sectional view through the heating unit showing one of the connectors between the upper and lower heating coils;

Fig. 4, a vertical sectional view through one of the concentric electric connections; and

Fig. 5, a detail section taken on the line 5—5 of Fig. 3.

55 My invention contemplates the use of any suitable frame or base for supporting the heater and blower units, but I prefer that the frame shall be in the form of a hollow pedestal so constructed that said units may be easily accessible for removal and replacement. More particularly, I prefer that the pedestal shall be constructed for the reception of said units through its top, which shall have a removable air delivery nozzle 85 permitting access to the interior of the pedestal. As an example I have shown the pedestal in the form of a hollow cylindrical column 6 having a bowl shaped top 7, dished inwardly as shown, and providing a relatively large air delivery opening defined substantially by the inner diameter of the tubular column. Said opening is covered by a perforate grate 8 forming a dished continuation of the pedestal top and forming 90 an air delivery nozzle. This grate may be secured in position by any suitable means, such for example as screws 9, which permit of its removal to give access to the interior of the pedestal column.

105 The heater and blower units may be suitably supported within the pedestal, either directly thereon or through the agency of an intermediate structure, such as the tubular casing 11, which has a flange 10 at its 110

upper end secured to the pedestal top by the screws 9. This casing carries at its lower end a suitable spider bracket 12 having two or more radial arms which support one part of a concentric electric connector, the construction of which will be described later. The blower unit or cage comprises in this instance a cylindrical casing 13 adapted to be slid lengthwise into the casing 11 and equipped at its lower end with a spider bracket 14 having a concentric electric connector complementary to that carried by the bracket 12. The casing 13 also carries a blower which may be of any suitable or preferred construction, and in the present example consists of an electric motor 15 attached to the casing through the agency of a bracket 16 and equipped with a fan 17 for producing and delivering a current of air upwardly through the channel formed by the cylindrical casing.

The electric connection between the stationary bracket 12 and the bracket 14, which with the motor casing is removable through the top, is so constructed that when placed in position the desired electric connection will be established. This connection, best shown in Fig. 4, includes lower connecting wires 18 and 19 and upper connecting wires 21 and 22. The wire 18 is connected to an inner socket terminal 23 which receives an inner plug terminal 24 connected to the upper wire 22. These terminals are insulated from an outer socket terminal 25 connected to the wire 19 and an outer plug terminal 26 connected to the wire 21. The inner and outer socket terminals 23 and 25 are supported on the bracket 12 through means of an insulation casing 27, and the inner and outer plug terminals 24 and 26 are supported on the bracket 14 by the insulation casing 28. It will thus be seen that both parts of the electric connection are concentrically disposed so that upon placing the blower casing in position an electric connection will be established between two sets of terminals. As shown in Fig. 1, the motor 15 is connected by wires 29 and 31 to the wires 21 and 22 respectively. The electric supply wires 32 and 33 are connected respectively to the wires 18 and 19, and a suitable switch is included in the circuit, as for example, the foot pedal switch 34 in the wire 33. It will be seen from the foregoing that the motor is included in an electric circuit adapted to be closed by the foot switch 34.

I have now devised a heater unit which may be quickly removed and replaced and which when in operative position, will be in parallel connection with the circuit just described. The heating elements are carried by a tubular casing 35 which fits within the casing 13 and carries at its lower end a spider bracket 36 equipped with one part of

an electric connection, the complementary part of which is carried by a spider bracket 37 fixed to the blower casing 13. Inasmuch as this electric connection is similar in construction to that shown in Fig. 4, a detail description thereof will not be required. It will suffice to say that the lower wires 38 and 39 connect to the inner and outer socket terminals respectively, and that the upper wires 41 and 42 connect to the inner and outer plug terminals respectively. The lower terminals 38 and 39 of this concentric electric connection are connected with the upper terminals 22 and 21 respectively of the lower electric connection, thus extending the parallel circuit to include the electric resistance elements. These elements may be of any suitable or preferred construction, and in the present instance I employ an upper and a lower set of heating coils designated generally by 41 and 42 respectively, as shown in Figs. 2 and 3. The individual coils are supported at their ends by vertical rods 43 spaced circumferentially about the casing 35. The upper and lower edges of this casing are shaped to provide tabs 44 turned inwardly, and thence upon themselves, as shown in Fig. 5, the inner sides of the tabs being perforated for the reception of the ends of the rods 43 and the outer sides serving as abutments for holding said rods against lengthwise displacement. A lining 45 of asbestos or any suitable insulation is provided at the inner side of the casing 35, being retained in position in part by the tabs 44. The heating coils of each set are connected at their ends in series to wire couplings 46 which in turn partially embrace and seat in the grooved insulation collars 47 supported on the rods 43. The coils in the upper and lower sets are arranged in planes at right angles to each other so as to most efficiently heat the air. The terminals 48 of each set of coils are connected to the connector plates 49 and 51, which are insulated by mica sheets 52 and connected respectively to the connections 41 and 42 of the upper part of the upper concentric electric connection.

From the foregoing, it will be evident that I have provided a pedestal in which a blower or fan unit and a heater unit may be readily positioned, and that I have further devised an electric circuit, certain connections of which are embodied integrally in the blower and heater units, so that upon placing these units in the pedestal in operative position the electric circuit is completed. In the present instance the supply wires 32 and 33 of this circuit and the lower electric connections are accessible by reason of the removable perforated grating 53, which grating affords an air inlet. When the parts are in the assembled relation shown in Fig. 1, the electric circuit

may be closed at will by closing the switch 34, thereby causing the fan to deliver an upward current of air through the channel defined by the tubular casing, this current 5 of air being heated by the electric coils and delivered upwardly through the nozzle 8. By reason of the relatively large diameter of the delivery nozzle and of the 10 perforated nozzle structure, the delivery will be modulated and diffused directly over the pedestal, although in a definite upward current, giving a greater drying area close to the heating coil than is possible with those constructions having a quite restricted 15 delivery mouth. It will also be manifest that by the provision of the self-contained blower and heater units, that is, with the electric connections intact, these units may be quickly and easily removed by an inexperienced and unskilled person and replaced by new units in the event that repairs are necessary. It follows that when repairs are required the fixture need not be put 20 out of use during the interval required for repairing, as a new unit may be substituted for the old. It should also be borne in mind that my invention is not limited to the use of separate blower and heater units, this being illustrated as a preferred form, 25 simply because of convenience in manufacture and other reasons. Instead the blower and heater might be embodied in a single unit as in effect is the case in the event that the motor unit casing 13, which extends 30 substantially to the nozzle 8, be lifted from the pedestal with the heater unit. It will be noted that by nesting the casings and providing concentric electric connections, the circuits may be broken and connected 35 simply by removal and replacement of the several casings.

It is believed that the foregoing conveys a clear understanding of the objects pre-faced above, and while I have shown in the 45 drawings but a single working embodiment, it should be understood that considerable change might be made in the construction and arrangement without departing from the spirit and scope of the invention as expressed in the appended claims; in which—

I claim:

1. In a lavatory fixture, the combination 55 of a pedestal, a heater and a blower unit therein, each unit having a tubular casing and an electric connection, said casings forming an air channel through which a current of air may be delivered upwardly, and an electric circuit including said connections, and permitting removal of said units with their respective electric connections.

2. A fixture of the character described 60 comprising a tubular pedestal having an open top, a perforate grate covering said top and providing an air delivery nozzle,

a tubular casing within said pedestal removable through said open top and providing an air channel through which air may be delivered upwardly to said nozzle, and a heating element and a blower within 70 said tubular casing for causing a current of heated air to be delivered upwardly therein.

3. A lavatory fixture comprising a hollow pedestal having a lower air inlet and an upper air delivery opening, an electric circuit within said pedestal, an electric motor and a heater connected in parallel in said circuit and adapted to be removed and replaced through said open top with their 75 electric connections intact, and a fan driven by the motor for delivering a current of air upwardly through the heater and said delivery opening.

4. In a fixture of the character described, the combination of a base having an air 85 inlet, a nozzle through which air is adapted to be delivered, an electric heating unit and a blower unit removably supported on the base and providing an air channel between said inlet opening and said delivery nozzle, 90 an electric circuit connecting the blower and heating elements, each of said units including a section of said circuit, and said circuit including detachable electric connections permitting removal of said units with their 95 respective circuit sections intact.

5. In a fixture of the character described, the combination of a pedestal, a stationary bracket in the pedestal carrying one part of a concentric connection, a blower unit 100 adapted to be positioned in said pedestal and equipped with a concentric connection complementary to that on said bracket and equipped at its upper end with one part of a second concentric electric connection, a heater unit adapted to be positioned in the pedestal and equipped with an electric connection complementary to the upper connection of the blower unit, and an electric 105 circuit connecting the heater and blower connections.

6. In a fixture of the character described, the combination of a pedestal, a blower unit 110 therein including a motor and a fan, an electric heating unit in the pedestal above the blower, and an electric circuit connecting the blower and heating units and including electric connections between said units adapted to open and close said circuit upon removing and replacing the heating 115 unit.

7. A lavatory fixture of the character described comprising an upright, hollow, cylindrical pedestal having an enlarged base, an air inlet near the base and an open top providing an air outlet, a tubular casing within the pedestal removable through said open top, a blower and a heating unit carried by and within said casing, 125 and an electric circuit connecting said motor 130

and heating unit including a foot operable switch supported on said base and adapted for closing and opening the circuit.

8. A fixture of the character described, comprising a tubular pedestal having an air inlet at its lower end and an air delivery nozzle at its upper end, a tubular casing within said pedestal equipped with a motor and a fan, a tubular casing above and concentric with the first mentioned casing and equipped with an electric heating unit, said casings forming an air channel between the air inlet and delivery nozzle, and an electric circuit connecting the motor and the heating element and including electrical connectors between said motor and heating unit adapted to open and close the circuit upon removal and replacement of the heating unit.
9. A fixture of the character described, comprising a tubular pedestal having an air inlet at its lower end and an air delivery nozzle at its upper end, a tubular casing within said pedestal equipped with a motor and a fan, a tubular casing above and concentric with the first mentioned casing and equipped with an electric heating unit, said casings forming an air channel between the air inlet and delivery nozzle, and an electric circuit connecting the motor and heating element and including quick detach-

able connections permitting removal of the heating unit from the motor unit with its section of the circuit intact.

10. In a lavatory fixture, the combination of a pedestal having an air inlet and an air outlet, a heater casing and a blower casing mounted in said pedestal and forming an air channel between said inlet and outlet openings, an electric circuit connecting the blower and the heater, and quick detachable connections in said circuit permitting removal of said units with their respective sections of the circuit intact.

11. In a fixture of the character described, the combination of a pedestal having a lower air inlet and an upper air outlet, a stationary spider bracket in the pedestal, a motor casing having an upper and a lower spider bracket, a motor and a fan mounted on said casing between said brackets, an electric heater casing in the pedestal above the motor casing and having a spider bracket, concentric electric connections between the two lowermost brackets and the two uppermost brackets, and an electric circuit connecting the motor and electric heater and in which said concentric connections permit quick removal of said casings with their respective sections of the circuit intact.

STANDISH S. BUDLONG.
